REGULATOR FOR FLUID COMPRESSORS

Ward Raymond, Easton, Pa., assignor to Pennsylvania Pump & Compressor Company, Easton, Pa., a corporation of Pennsylvania

Application May 16, 1932, Serial No. 611,538

6 Claims. (Cl. 230—24)

This invention relates to regulators for air or gas compressors or the like and more particularly to novel means for regulating the unloading and loading of the compressor in a number of distinct steps so that the volume of fluid compressed may be varied with the demand upon the compressor and the discharge pressure kept at substantially constant pressure under all loads of the compressor.

10 In variable volume compressors such as disclosed in this application, a series of pressure operated unloading devices are employed, each effecting a partial unloading of the compressor, so that the compressor capacity may be varied 15 in accordance with the operation of the unloading devices, these unloading devices being individually operated by a regulator acted upon by the varying pressures within the receiver of the compressor to move the devices to positions for 20 loading and unloading the compressor.

An object of the present invention is to provide a regulator or governor mechanism to control the operation of said unloading devices, this mechanism being comparatively simple in construction, 25 positive in operation, and such that the receiver pressure may be kept within close variations of pressure during wide fluctuations in demands upon the compressor.

More specifically, the present invention comprises a plurality of individually operating distributing valves for controlling the distribution of fluid under pressure to the individually operated unloading devices each unloading device serving to partially unload the compressor, these 35 distributor valves being in turn individually operated and controlled through electrically operated means by mechanism acted upon by receiver pressure, variations of this pressure serving to successively actuate the individual distributor valves 40 in their proper order.

And finally it is an object to employ mercury switches oscillated to opened and closed positions by movement of a regulator actuated by variations in receiver pressure, these switches when 45 closed serving individually to energize electromagnets and when open energizing other electromagnets respectively controlling fluid valves for the admission and withdrawal of fluid under pressure to and from the different unloader devices.

50 With the above and other objects in view my invention includes the features of construction and operation set forth in the following specification and illustrated in the accompanying drawing.

55 In the accompanying drawing annexed hereto

and forming a part of this specification I have shown my invention embodied in a single cylinder air compressor, but it will be understood that the invention can be otherwise embodied and that the drawing is not to be construed as defining or limiting the scope of the invention, the claims appended to this specification being relied upon for that purpose.

In the drawing:

Figure 1 is a front elevation of the control mechanism showing the connections to a compressor cylinder.

Fig. 2 is a side elevation of a portion of the controller mechanism.

Fig. 3 is an enlarged view of one of the electromagnetically operated valves for controlling the supply of fluid to the unloader devices, and

Fig. 4 is an enlarged view of one of the mercury switches.

In the above mentioned drawing I have shown but one embodiment of the invention which is now deemed preferable, but it is to be understood that changes and modifications may be made within the scope of the appended claims without departing from the spirit of the invention.

Briefly and in its broadest aspect my invention may include the following principal parts: First, a compressor cylinder having a plurality of unloading means operated by variations in discharge pressure, each acting to partially unload the cylinder; second, individual valves controlling admission and exhaust of fluid to and from said unloading means; third, electromagnets operatively connected to said valves for actuating said valves; fourth, switches individually controlling the energizing of said magnets; and fifth, pressure responsive means operating at slightly varying pressures to actuate said switches.

Referring more particularly to the figures of the drawing, an air compressor cylinder is shown at 10 in which the piston 11 reciprocates in the usual manner for compressing the fluid. In the cylinder 10 the unloading and loading is accomplished by four individual unloading means 12 operating respectively upon four valves 13 (one only being shown) controlling admission of fluid being compressed to receivers or clearance pockets 14. It is to be understood, however, that the present unloading or controlling means illustrated and described in this specification may be employed with any form of compressors employing other methods of unloading.

The control or governing apparatus for the unloading means 12 embodies a pressure actuated lever 15. This lever 15 is pivotally supported at

60

an intermediate point, one end of the lever engaging a member 16 attached to the center of a pressure diaphragm 17. The opposite end of the lever 15 is suitably weighted by weights 18 suspended as will presently be described. Actuated by oscillation of the lever 15 is a vertically movable rod 19 on which are mounted spaced collars 20. Preferably the lever 15 has attached to it a depending arm 21 the lower end of which is 10 attached to a bar 22 into which the lower end of rod 19 is fastened.

By reference to Fig. 1 it will be seen that the lever 15 moves from slightly below horizontal position to slightly above horizontal. The link 15 23 connected to the weights 18 moves from one oblique position to another below the horizontal. These oblique positions are of greater angle than the positions of the lever 15. It follows, therefore, that as the lever rises by increased pressures 23 above the diaphragm 17 the weights 18 move slightly outwardly along the lever 15. The pressure required to raise the lever to successively higher positions increases slightly by reason of the slightly increased arm at which the weights 25 18 act upon the lever 15. To the enclosed space above the diaphragm 17 fluid under pressure may be admitted directly from the compressor receiver (not shown). For this purpose a connection 24 is provided. The oscillated position of the lever 15 therefore varies with variations of 30 the discharge pressure of the compressor.

Adjacent the collars 20 on the vertically disposed rod 19 are electric switches 25, those shown being of the mercoind type. These switches 25 35 include a tiltable tube 26 containing a small amount of mercury which in one oscillated position of the tube 26 covers the terminals of cables 27 entering the tube. In the other oscillated position these terminals are above the level of the 40 mercury. By oscillating this tube 26 therefore an electric circuit through the cables 27 may be closed or opened. For the purpose of oscillating the tube 26 an arm 28 outstanding from the switch 25 extends to and is moved by engagement with one of the collars 20. In the 45 position shown in Fig. 4 the switch 25 maintains its circuit open, and when oscillated by movement upward of the rod 19 closes its circuit. The switches 25 are successively operated by continuous 50 upward movement of the vertical rod 19 as the collars 20 are at successively greater distances from the different arms 28. As the rod 19 starts its movement upward the lowermost switch 25 first is actuated and then the second and so 55 on for as many switches as may be provided. To retain the tube 26 of a switch 25 resiliently in either of its oscillated positions a spring 29 may be mounted on the member 30 carrying the arm 28. The resilience of spring 29 retains the member 30 in one of its positions but permits movement of the tube 26 by slight pressure against the arm 28. The tube 26 may be pivoted at 31 to the frame of the switch and connected to the member 30 by a short connecting arm 32. As 60 these mercoind switches are well-known and form no part of the present invention, further description of their specific construction is not thought to be necessary.

The pressure operated unloading devices 12 65 have fluid under pressure admitted to them through individual valves 35. Each of these valves 35 is electromagnetically operated by the coil 36 associated therewith and which may be energized by their respective switches 25 being tilted to one oscillated position. With a valve

35 open fluid is admitted to the outer end of a device 12 which forces a piston in a direction to force a valve 13 to an open position. This latter valve 13 of which there may be one for each switch 25 and electromagnetic valve 35 admits a portion of the fluid being compressed to a clearance pocket 14 thus fractionally unloading the cylinder as is well-known.

The structure of valve 35 is indicated in Fig. 3. A solenoid 37 within the coil 36 has a needle or conical valve 38 at its lower end. With the coil 36 energized the armature is forced upwardly to move valve 38 from its seat 39. Fluid may therefore be admitted from connection 40 supplied with receiver pressure to the connection 41 leading to one of the unloader devices 12. With coil 36 deenergized the armature 37 rests with its entire weight upon the seat 39 so that valve 38 is effectively closed. Fluid therefore is prevented from entering connection 41 and the unloader device 12 is not operated.

To release the pressure from the connections 41 to render the unloader devices 12 inoperative a second series of valves 42 is provided. These valves 42 are in every way similar to valves 35 but are connected as shown in Fig. 2 in a manner opposite to valves 35. Fluid enters valves 42 from connection 41 through a branch 43 therein and may be admitted to atmosphere from the connection 44.

Each unloader device 12 has its individual connection 41, valves 35 and 42 and switch 25. The first upward movement of lever 15 operates on device 12 through one of the switches 25 and valves 35 and 42. Continued upward movement of lever 15 operates another unloader device 12 through the second switch 25 and so on. With a slight drop in receiver pressure and consequent lowering movement of the lever 15 a collar 20 moves away from an arm 28 permitting a switch 25 to return to open position thus de-energizing the coil 36 of valve 35. This allows valve 35 to close. Simultaneously the valve 42 is opened so that pressure may exhaust from the connection 41.

The coils for the valves 35 and 42 are wired in a circuit so that when one coil is energized the other is de-energized. With the switch in the position shown in Fig. 4 the coil 36 for valve 35 is de-energized, while the coil for valve 42 is energized thus opening valve 42. In this position of the valves 35 and 42 no pressure can build up in the connection 41 so that the unloader device 12 for that set of valves is in position for normal operation of the compressor.

What I claim is:

1. The combination with a variable volume air or gas compressor, of pressure operated unloading devices for loading and unloading the compressor, distributor valves for controlling admission of pressure fluid individually to said unloading devices, individual exhaust valves for said devices a solenoid connected to each of said distributor and exhaust valves for operating them, switches for controlling energizing of said solenoids whereby but one solenoid for an unloading device is energized at a time, and a bar having an undulating surface and moved upon variances in pressure of fluid compressed for operating said switches.

2. In a variable volume compressor, the combination with a cylinder, of a plurality of pressure operated unloading devices, each acting to partly unload the cylinder, a distributing valve for supplying pressure fluid to each of said un-

- loading devices, exhaust valves for said devices independent electric operating means associated with each of said valves, whereby but one valve for an unloader device is open at a time and 5 a bar having an undulating surface and moved upon variances in pressure of fluid pumped for operating said electrical operating means.
3. In a variable volume compressor, the combination with a cylinder of a plurality of pressure operated unloading devices each acting to partly unload the cylinder, a distributor valve for supplying pressure fluid to each of said unloading devices, exhaust valves for said devices independent electric operating means associated with each 10 of said valves, whereby but one valve for an unloader device is open at a time, and a rod having a series of projections thereon movable upon variances in pressure of fluid pumped for controlling energizing of said electrical means.
- 20 4. In a variable volume compressor, the combination with a cylinder, of a plurality of pressure operated unloading devices each acting to partly unload the cylinder, a distributing valve for supplying pressure air to each of said unloading devices, independent electric operating means associated with each of said valves, whereby but one valve for an unloader device is open at a time, a rod having a series of projections thereon movable upon variances in pressure of fluid 25 pumped for successively controlling energizing of said electrical means, and a compensator structure associated with said last named means for automatically adjusting it to increase or decrease 30

- the pressures required for operating said means.
5. The combination with a variable volume air or gas compressor, of pressure operated unloading devices for loading and unloading the compressor, admission and exhaust valves of the needle type for controlling admission and exhausting of pressure fluid to and from said unloading devices, a solenoid connected to each of said distributor valves for operating them, switches for controlling energizing of said solenoids, and a bar having spaced enlargements thereon moved axially upon variations in discharge pressure of the compressor, said switches being disposed adjacent said projections for successive operation thereby.
6. The combination with a variable volume air or gas compressor, of pressure operated unloading devices for loading and unloading the compressor, distributor valves for controlling admission of pressure fluid to said unloading devices, a solenoid connected to each of said distributor valves for operating them a solenoid controlled exhaust valve for each of said unloading devices, switches for controlling energizing of said solenoids, and a vertically disposed bar moved axially upon variations in discharge pressure of the 100 compressor, said bar having spaced projections thereon and said switches having operating arms extending into the path of and actuated by said projections whereby said switches may be successively operated by movement of said rod in 105 one direction.
